AXEL G. JENSEN, OF RED BANK, NEW JERSEY, ASSIGNOR TO WESTERN ELECTRIC COMPANY, INCORPORATED, OF NEW YORK, N. Y., A CORPORATION OF NEW YORK.

ELECTRIC WAVE TRANSLATION SYSTEM.

Application filed December 4, 1924. Serial No. 753,813.

This invention relates to electric wave translation systems and more particularly to space discharge tube systems wherein the production of undesired oscillations is prevented. 5 It is now well known that, in a space discharge tube system, oscillations will be generated when the input and output circuits of the tube contain reactances of the proper kind and of the proper value. These oscillations 10 are generated by virtue of the amplifying action of the tube, and by virtue of the coupling afforded between these circuits by the inherent capacity between the tube electrodes and the external leads associated therewith. On the 15 basis of this knowledge, systems have been devised in which the tendency to generate undesired oscillations is reduced, by providing a balancing capacity for neutralizing the tube electrode capacity.

20 It has been found, however, that when tubes of great amplifying power are employed, or when a large number of tubes are placed in tandem, a system arranged for capacity neutralization may provide a new path in which 25 parasitic oscillations may be generated. The invention to be hereinafter described provides a solution of this problem.

An object of the invention is to prevent the 30 generation of parasitic oscillations in wave translation systems, particularly those including space discharge devices.

Another object is to so alter the reactance of wave translation systems or space discharge tube systems as to avoid a condition favorable 35 to the generation of oscillations.

A further object is to prevent the flow of oscillatory waves through specified paths in a space discharge tube system.

An additional object is to prevent the flow 40 of undesired oscillatory waves by impeding them.

A feature of the invention is a space discharge tube system provided with an impedance element for preventing the flow of 45 oscillatory currents in the system.

Another feature is a space discharge tube system provided with paths including resistance, whereby an oscillatory condition of the system is avoided.

50 A further feature is an arrangement of space discharge tubes having the associated circuits therewith so balanced that the generation of parasitic oscillations is prevented.

The present invention involves certain principles which are applied to systems of space

discharge tubes to obtain the objects above enumerated and others. In order to prevent undesired oscillations in systems of space discharge tubes, the circuits included therein may be so designed that paths, wherein oscillatory currents tend to flow, will contain an element or elements for impeding oscillations. For example, the impedance element may be a resistance. In another instance, oscillations may be prevented by providing reactance elements in certain paths of the system such that no tendency for oscillations to build up will be present. As an example of this, a space discharge amplifier may have either its input or output circuit or both circuits balanced by means of a capacity arranged to neutralize the effect of interelectrode capacity of the space discharge tube. In arrangements of this kind, heretofore known, parallel paths between the tube input and output circuits are provided wherein oscillations may be generated. This invention provides means for preventing oscillations in these paths by providing, for example, reactance of a particular kind at certain points 75 therein where reactance of a different kind would be required to bring about a condition favorable to the generation of oscillations. Again, by properly balancing both the input and output circuits of a space discharge tube, 80 parasitic oscillations are prevented.

The invention is described in detail in the following specification read in connection with the attached drawing including several figures, wherein like reference characters 85 have been used to indicate like parts.

Fig. 1 represents schematically a space discharge tube system having an oscillation impeding element.

Fig. 2 represents a system slightly different 95 from that shown in Fig. 1.

Fig. 3 represents a space discharge tube system wherein oscillations are prevented by suitable reactances in its input circuit.

Fig. 4 represents a single tube amplifier 100 having balanced input and output circuits.

Fig. 5 represents an amplifier having an output circuit provided with capacity reactance for preventing oscillations.

Fig. 6 represents a modification of the system shown in Fig. 5.

In Fig. 1, a space discharge tube 10 having anode, cathode and control electrodes 11, 12 and 13, respectively, is arranged in a circuit including an impedance element 14 and a 110

capacity element 15 for preventing oscillations in the system. The space discharge tube 10 has an input circuit connected to its control electrode and cathode which includes a resonant circuit 17, comprising a condenser 18 and inductance 19, a polarizing battery 20, and resistance 14. Resonant circuit 17 may be tuned by adjusting condenser 18. The mid-point of the winding of coil 19, is connected to the cathode by a path including the grid polarizing battery 20 and resistance 14. One terminal of the winding of coil 19 is connected to the control electrode 13, whereas its opposite terminal is connected to the anode 11 by a path including condenser 15. The output circuit of tube 10 extends from anode 11, through an inductance 24 and a source of space current 23 to its cathode. The condenser 25, shown in dotted lines, represents the inherent capacity between the anode 11 and control electrode 13 of tube 10 plus the capacity of the leads connected to these electrodes.

Waves to be amplified may be supplied to the input circuit through the winding of coil 19 which also represents a transformer, a wave collecting conductor—such as a loop antenna, or similar device. Amplified waves may be transmitted to any suitable apparatus external to the system by suitable coupling means associated with the coil 24.

In amplifying systems as ordinarily arranged the capacity 25, shown in dotted lines, by providing a feed back path from the anode 35 to the control electrode of the tube, permits the transfer of waves from its output circuit to its input circuit which may cause the production of undesired oscillations. In an effort to neutralize the effect of capacity 25, the anode 11 is connected to the cathode 12 by a path including the balancing condenser 15. This path is in parallel with that including the capacity 25. Varying currents flow in the two parallel paths through the 40 respective halves of coil 19 in such manner as to induce electromotive forces therein which are theoretically equal and opposite, so that no potential variations are impressed upon control electrode 13.

In practice, it has been found that the balancing capacity 15 in parallel with the tube capacity 25 constitutes new paths in which oscillations may be generated, especially, when tubes of high amplifying power are employed, unless additional means is produced to prevent their occurrence. This fact will be understood when we consider that the input circuit of tube 10 contains an inductance, represented by the difference between the self-inductance of coil 19 and the mutual inductance between its two halves, and the output circuit contains the inductance 24. It is well known that a space discharge tube system, including inductive reactances in both the input and output circuits and capac-

ity coupling between them, will generate oscillations at certain frequencies for which these reactances cooperate to constitute a resonant circuit.

In order to prevent these reactances inherent in the system from producing oscillations the resistance 14 is provided. This resistance is included in the path traversed by currents tending to generate oscillations and, by offering a high impedance to these currents, prevents them from reaching an amplitude such that the system will oscillate.

Resistance 14 may be of such value as not only to prevent oscillations but also to cause modulation or demodulation to take place in the input circuit. The tube 10 then becomes a modulator or detector as the case may be.

The system of Fig. 2 is similar to that of Fig. 1 with the exception that resistance 14 is replaced by two resistances 26 and 26' connected respectively between the cathode of tube 10 and the two outer terminals of the winding of coil 19. These resistances are included in the parallel paths between the anode and cathode and are of such value as to greatly impede the flow of oscillatory waves and, if desired, to cause the tube to operate as a distorting device for the impressed waves, whereby detection or modulation of these waves may be effected. Whether or not detection or modulation takes place depends upon the value of the resistances which may be varied until they are of a value suitable for the purpose desired.

In the arrangement shown in this figure 100 the inductance of coil 19 is excluded from the parallel paths including capacity 25 and resistance 26 on the one hand and condenser 15 and resistance 26' on the other. So far as concerns the energy fed back from the output circuit to the input circuit, there is no inductive reactance included in these paths on the input side of tube 10, hence they are effectively aperiodic. A condition such as to preclude the generation of oscillations therefore exists in the circuit.

In Fig. 3 the inductance of the coil 19 is also excluded from the parallel oscillatory paths which contain the condenser 27 shunted by resistance 29 and condenser 28 shunted by 115 resistance 30 in addition to the capacity 25 and condenser 15 respectively included in these paths. Since, in the portions of the parallel paths on the input side of tube 10, there is included no inductive reactance, oscillations cannot be generated in these paths. Resistance 29 provides a leak path between the control electrode and cathode of tube 10 around the condenser 27. A similar resistance 30 is connected in shunt to condenser 28 for balancing the resistance 29. By adjusting condensers 27 and 28 an accurate balance of the parallel paths may be obtained, and the input circuit may be tuned to the frequency of the impressed waves.

An additional arrangement for preventing oscillations, comprising parallel paths between the cathode and anode of a space discharge tube, is illustrated in Fig. 4. Oscillations are prevented in this arrangement by balancing both the input and the output circuits of the tube.

Resonant circuits 17 and 17' are included respectively in the input and output circuits 10 of tube 10, and these resonant circuits include as their inductive elements the coils 19 and 19', respectively. Condenser 15' is arranged to balance the capacity 25 between the anode and control electrodes, as already explained. Condensers 15 and 15'' provide two additional parallel paths complementary to the parallel paths through capacities 25 and 15' whereby oscillation currents tending to flow therein are neutralized. Each of these condensers has a capacity substantially equal to the capacity 25 between the anode and control electrode. Since both the input and output circuits of the tube are balanced, it is impossible for energy from the output circuit to be supplied to the input circuit in such manner as to establish parasitic oscillations.

In Fig. 5 an amplifier system is illustrated in which only the output circuit is balanced and the inductance of resonant circuit 22 is excluded from the parallel paths between the anode and control electrode to prevent oscillations, as was done in the input circuit in Fig. 3. Condensers 27' and 28' render the parallel paths between the anode and cathode 35 of tube 10 in this figure capacitively reactive so far as the output circuit of the tube is concerned, hence oscillations cannot be generated in these paths because, as explained above, of the lack of inductive reactance therein on 40 one side of tube 10. The choke coil 37 is designed to have a very large inductance so that for frequencies at which oscillations might otherwise occur the resultant reactance of the output circuit is capacitive. In other 45 words the inductance is made so large that the reactance is substantially pure capacity reactance. One terminal of the balancing condenser 15, in this instance, is connected to the terminal of condenser 28' remote from 50 the cathode, while its other terminal is connected to the control electrode. This condenser functions in the same manner as the corresponding condensers in the previous figures.

A second space discharge tube amplifier 35 is here shown with its input circuit capacity coupled to the output circuit of tube 10 for obtaining a step-up of voltage of translated waves. It will be noted that the input circuit 60 of tube 35 is connected across both condensers 27' and 36, which are included in series in a closed loop including the resonant circuit 22 and condenser 28', whereas the output circuit of tube 10 is only connected across condenser 65 27'.

By this arrangement there is provided a step-up in voltage between the output circuit of tube 10 and the input circuit of tube 35. It is thus evident that condenser 27' functions not only as means for preventing singing in 70 the system, but also as a voltage multiplying means.

The amplifier circuit illustrated in Fig. 6 is very similar to that illustrated in Fig. 5, but the input circuit is balanced, and the output 75 circuit is provided with only capacitive reactance so that an oscillation condition is avoided.

In particular instances the invention has been found effective when employed with 80 tubes having equi-potential cathodes, i. e. cathodes heated by induction or heat radiation such as described in the patent to Nicolson 1,459,412 granted June 19, 1923, but this statement should not be taken to indicate 85 that the utility of the invention is in any manner limited to a particular type of tube.

Although, for the purpose of explaining the invention, it has been described in connection with certain specific circuit arrangements, the principles involved are capable of general application to a range of equivalents not specifically described; but which will readily occur to persons skilled in the art, and consequently this invention is to be limited only as indicated by the scope of the appended claims.

What is claimed is:

1. In a space discharge tube system, a three electrode space discharge tube, input and output circuits for said tube, means for balancing the capacity between certain electrodes of said tube to prevent oscillations at frequencies near the frequencies of the currents impressed on said input circuit, and a non-reactive impedance cooperating with said balancing means to prevent the generation of oscillations in the system at frequencies above the frequencies of the currents impressed on said input circuit.

2. In a space discharge tube system, a three electrode space discharge device, a resonant circuit, electrodes of said device being connected to electrically separate points in said resonant circuit, means connected to balance the capacity between two of said electrodes to prevent oscillations at frequencies near the frequencies of currents impressed on said input circuit, and a resistance adapted to impede waves tending to establish oscillations, whereby the generation of oscillations is prevented.

3. In an amplifier, a space discharge tube, comprising an anode, cathode and control electrode, a plurality of paths from said anode to said cathode, and means including a reactance and a resistance in series in one of said paths cooperating to prevent the production of oscillations having a frequency near the frequency of the currents impressed on the

discharge tube and oscillations having a frequency above the frequency of the currents impressed on the discharge tube.

4. In a circuit including a space discharge tube having an input circuit and an output circuit, means for preventing "singing" caused by the internal capacity of the tubes, comprising a capacity connected between said input and output circuits, and means comprising a resistance included in said input circuit in the path of waves tending to establish oscillations for preventing the generation of currents having frequencies different from the frequencies of the currents impressed on the tube.

5. In an amplifier, a space discharge tube having three electrodes and circuits associated

therewith for amplifying high frequency waves, said amplifier including a plurality of paths for waves tending to produce sustained oscillations, an impedance in one of said paths of one kind adapted to prevent oscillations having a frequency near the frequency of the currents impressed on the amplifier, and an impedance in another of said paths of a different kind adapted to prevent oscillations having frequencies different from the frequency of the currents impressed on the amplifier.

In witness whereof, I hereunto subscribe my name this 1st day of December, A. D. 1924.

AXEL G. JENSEN.
